(57) **CLAIM**

The ornamental design for a seat, as shown and described.

DESCRIPTION

FIG. 1 is a perspective view of a seat shown in the form of a seat in accordance with my invention;

FIG. 2 is a front elevation view of the seat shown in FIG. 1;
FIG. 3 is a rear elevation view of the seat shown in FIG. 1;
FIG. 4 is a right side elevation view of the seat shown in FIG. 1;

FIG. 5 is a left side elevation view of the seat shown in FIG. 1;

FIG. 6 is a top plan view of the seat shown in FIG. 1;

FIG. 7 is a bottom plan view of the seat shown in FIG. 1;
FIG. 8 is a perspective view of the seat shown in FIG. 1 with
cushions disposed thereon;

FIG. 9 is a perspective view of a seat shown in the form of a sofa in accordance with my invention;

FIG. 10 is a front elevation view of the seat shown in FIG. 9;

FIG. 11 is a rear elevation view of the seat shown in FIG. 9;
FIG. 12 is a right side elevation view of the seat shown in FIG. 9;

FIG. 13 is a left side elevation view of the seat shown in FIG. 9;

FIG. 14 is a top plan view of the seat shown in FIG. 9;

FIG. 15 is a bottom plan view of the seat shown in FIG. 9;
and,

FIG. 16 is a perspective view of the seat shown in FIG. 9
with cushions disposed thereon.
